DESIGN FOR A COASTER

Georgine H. Wright-Clark, Rye, N. Y.

Application April 10, 1946, Serial No. 128,439

Term of patent 3½ years

(Cl. D44—7)

To all whom it may concern:

Be it known that I, Georgine H. Wright-Clark, a citizen of the United States of America and resident of Rye, county of Westchester, State of New York, have invented a new, original, and ornamental Design for a Coaster, of which the following is a specification, reference being had to the accompanying drawing, forming a part thereof and of which:

Fig. 1 is a top view of a coaster, showing my new design; and

Fig. 2 is a cross-sectional view taken on the line 2—2 of Fig. 1.

I claim:

The ornamental design for a coaster, as shown.

GEORGINE H. WRIGHT-CLARK.
